UNITED STATES PATENT OFFICE.

GERRONE W. BURNS, OF INDIANAPOLIS, INDIANA.

CIGAR-CUTTER.

SPECIFICATION forming part of Letters Patent No. 282,155, dated July 31, 1883.

Application filed September 2, 1882. (No model.)

To all whom it may concern:

Be it known that I, GERRONE W. BURNS, of the city of Indianapolis, county of Marion, and State of Indiana, have invented certain 5 new and useful Improvements in Cigar-Cutters, of which the following is a specification.

The object of my said invention is to produce a cigar-cutter in which the cutting-knives shall move simultaneously toward or 10 from each other, whereby the cigar may be cut from both sides toward the center. This object is accomplished by mounting the knives in slides so arranged that the cutting-edges shall pass close to each other during the process 15 of cutting the cigar, and shall be operated by various bars and levers connected together, as will be hereinafter more particularly described.

Referring to the accompanying drawings, 20 which are made a part hereof, and on which similar letters of reference indicate similar parts, Figure 1 is a perspective view of a cutter embodying my said invention; Fig. 2, an end elevation of the same; Fig. 3, a longitudinal vertical section thereof; and Fig. 4, a view 25 similar to Fig. 2, except that the various parts are in the position they occupy after the cutter has been operated.

In said drawings, the portions marked A 30 represent the base or block on which the mechanism of my improved cutter is mounted; B, the frame-work of said mechanism; C D, the sliding cutter-knives; E F G H I, a series of levers, links, and bars by which one of said 35 knives is operated; and J, a plunger by which the operating force is applied to the mechanism.

The base or block should have a groove, a, 40 therein, as shown, to receive and guide the cigar, and a graduated scale, a', or a suitable gage, by which the length of the cigar may be determined.

The frame-work B is securely attached to the base A, by means of screws b, or otherwise, 45 in such position that when the knives are apart, as shown in Figs. 1, 2, and 3, a cigar placed in the groove a may be passed freely between said knives. Said frame-work contains proper slides and bearings for the mechanism of the cutter, as shown.

The knives C and D are each mounted in slides in the frame B, where they are secured, either by screws c c' d, as shown, or some other suitable fastening devices, in such relation that the edges thereof will pass close to each other as they are forced up and down. The knife C is operated directly by the plunger J, to which it is connected by a screw or pivot, j. The knife D is operated by the system of levers, connecting-rods, and links 60 shown.

A lever, F, is connected to the frame B by a pivot, f. A link, E, connects this to the knife D, pivots e and e' being the means of attachment. A lever, G, is pivoted to the knife 65 C or plunger J, preferably by the same pivot that connects said knife and plunger together, and is connected by a link, I, to the frame B, said link being pivoted to said frame by the pivot i, and to said lever by the pivot g. A 70 connecting-bar, H, connects the two levers F and G, being pivoted to the same by pivots f' and g', thus establishing a connection between the two knives, which causes them to approach or recede from each other uniformly. 75

The plunger J is an ordinary device, used frequently in hand-stamps and such like articles. It is commonly forced downwardly by pressure or a blow from the hand, and thrown back into position for further use by the coiled 80 spring J', which surrounds its shank.

The operation of my improved cutter may be recapitulated as follows: A newly-made cigar is laid in the groove in the base A, with the end which is to be squared extending through 85 between the knives. The plunger J is then forced down, carrying with it the knife C, and through the series of levers, rods, &c., forcing up the knife D. These knives pass each other, cutting off the end of the cigar, the 90 center of said cigar, owing to the simultaneous movement of the knives, being the part last severed. The spring J' forces the mechanism back into position for further use.

Having thus fully described my said invention, what I claim as new, and desire to secure by Letters Patent, is—

The combination of the lower cutting-knife, the lever F, pivoted to the frame, and connected to said knife at one end and to the con- 100

necting-bar H at the other, said connecting-bar, the lever G, connected to the frame by means of the link I at one end, to the upper knife at the other, and to the connecting-bar 5 at an intermediate point, said upper knife, and the plunger or lever by which the whole is actuated, substantially as set forth.

In witness whereof I have hereunto set my

hand and seal, at Indianapolis, Indiana, this 30th day of August, A. D. 1882.

GERRONE W. BURNS. [L. S.]

In presence of—

C. BRADFORD,
E. W. BRADFORD.
